LASTING TOOL

John T. Riddell, Evanston, Ill.

Application July 5, 1938, Serial No. 217,350

5 Claims. (Cl. 12—109)

This invention relates to lasting tools for shoe making and particularly to stretching and pulling devices for drawing the toe portion of a shoe upper tightly over the toe of a last during the 5 lasting operation.

The main objects of this invention are to provide an improved stretching tool for lasting the toe of a shoe; to provide such a device that will more quickly, easily and firmly grasp the leather 10 margins of a shoe upper; to provide a stretching tool that can be fulcrumed on the sole surface of a last and at the same time reach over and below the edge of the same to grasp the margin of an upper; to provide such a device capable of more 15 certain and forceful gripping and pulling action; and to provide such a device of more simple construction and lower manufacturing cost.

Specific embodiments of this invention are shown in the accompanying drawing in which:

20 Fig. 1 is a sectional view in elevation showing the application and use of the improved tool.

Fig. 2 is a perspective view of one form of the tool.

Fig. 3 is an end view of the same, and,

25 Fig. 4 is a perspective view of a common form of lasting tool modified to embody this invention.

As shown in the drawing my improved lasting tool comprises a fulcrum portion, a nose portion spaced forwardly of the fulcrum portion to provide an open space or gap therebetween, and a plurality of spaced pointed prongs projecting outwardly from the nose portion for engaging and gripping the margin of a shoe upper.

In the form shown in Figs. 1, 2, and 3, the tool 35 body is formed from a single piece of round metal stock bent at its middle to form a substantially semi-circular loop or nose portion 1, turned radially inward from opposite sides of the loop to provide lateral arms or a fulcrum portion 2, and 40 then extend diametrically outward at right angles to the fulcrum portion to provide a handle portion 3. The nose portion 1, opposite the handle 3, is then turned upwardly on a chord of the semi-circular loop, at about midway between the 45 tip of the nose portion and the arms or fulcrum 2 so as to be at an angle of approximately 45° from the plane of the sides of the loop and the handle 3 is bent upwardly at the fulcrum portion so as to be at an angle of about 30° from 50 the plane of the sides of the loop.

The gripping or leather engaging means comprise a plurality of spaced prongs 4 which are arranged to project from the upper surface of the nose portion 1 in a position to catch upon and 55 be driven into any material against which the

nose portion is engaged. As shown, the prongs 4 are pointed pin-like members mounted in the nose portion of the tool by being set and suitably fastened in individual sockets drilled into the nose portion body. The prongs are set so as to project substantially normal to the surface of the nose portion and are preferably spaced on each side of the fore and aft center line of the tool. Such spacing of the prongs 4 is to leave the center line area of the nose portion clear so that a central seam, not shown, in the upper will not become engaged and perhaps torn open by the prongs during manipulation of the tool. Also, by spacing the prongs 4 symmetrically on each side of the tool center line, the two halves of 10 the shoe upper, joined by the beforementioned central seam, will be equally, uniformly, and simultaneously stretched and drawn during the lasting operation.

Thus, when the tool is placed over the toe of 20 a last 5, as shown in Fig. 1, with the fulcrum portion 2 resting on the sole surface of the last, the nose portion 1 may be projected below and under the toe of the last, so that the prongs 4 will readily engage the margin 6 of the toe portion of an upper 7.

Then upon shifting the handle 3 in the direction of the arrow 8 in Fig. 1, toward the heel of the last 5, the tool will pivot on the fulcrum 2 and turn the nose portion 1 upwardly over the 30 toe of the last and somewhat rearwardly so as to stretch and draw the toe portion of the upper 7 tightly over the last in one simple operation, after which the said margin 6 may be tacked down and secured in the usual manner to the insole 9 which is disposed on the sole surface of the last 5.

In Fig. 4 the herein-described invention is shown embodied in a lasting tool that is generally of an old and well-known form comprising pincers having relatively long downwardly curved toothed jaws 10, disposed one above the other, operated by handles 11, and having a hammer head 12 mounted on the bottom side of the lower jaw between the downwardly curved end thereof and the pivot 13 of the handles 11.

As modified to embody my improvements, the hammer head 12 is located close to the pivot 13 to provide a large gap between the forward edge of the head and the tips of the downwardly 50 curved jaws 10 and the forward side of the head 12 is flattened as at 14 to provide a straight transverse fulcrum edge 15. Also, the outer end margin or nose portion of the upper jaw 10 is provided with a plurality of spaced pointed 55

prongs 16 which project outwardly from the said upper jaw as shown.

These prongs 16 are mounted on the upper jaw 10 in any suitable manner, as by drilling sockets 5 and setting the prongs therein. Also the prongs 16 are spaced equally on each side of the center line of the jaws 10 to provide for the passage of a seam and for equal pull on each side of the seam, as heretofore mentioned with regard to the 10 tool shown in Figs. 1, 2, and 3.

The principal advantages of my improved lasting tool are found in its use for lasting the toe portions of shoe uppers and reside in the 15 ease and rapidity with which that operation can be accomplished. Also a more consistent uniformity in the stretching of the upper over the toe of the last is had as the pull is distributed evenly and is simultaneous on each side of the center line. Other advantages are found in the 20 arrangement providing a relatively wide gap between the fulcrum and the upper engaging nose portion of the device, whereby the nose portion can be turned below the toe of the last to obtain a secure grip on the upper margin and 25 then, pivoting on the fulcrum, turned upwardly and rearwardly to tightly and perfectly stretch the toe portion of the upper in one simple operation.

Other advantages are found in the simplicity 30 of the construction and its low cost of manufacture.

Although but two specific embodiments of this invention are herein shown and described, it will be understood that details of the constructions 35 shown may be altered or omitted without departing from the spirit of this invention as defined by the following claims.

I claim:

1. A lasting tool comprising a handle, means 40 adjacent one end of said handle providing a transverse fulcrum arranged to rest against the surface of a shoe sole, a nose portion spaced forwardly of said fulcrum and extending parallel therewith, said nose portion being arranged to 45 provide an open gap between its forward end and said fulcrum and to reach forwardly over the toe end of said sole, and a plurality of outwardly projecting prongs spaced along the forward end of said nose portion, all arranged whereby said

nose portion will move and pull principally in an upward direction when said tool is rocked on said fulcrum.

2. A lasting tool comprising a handle, means adjacent one end of said handle providing a 5 transverse fulcrum arranged to rest against the surface of a shoe sole, an outwardly curved nose portion spaced forwardly of said fulcrum and extending substantially parallel therewith, said nose portion being arranged to provide an open 10 gap between its forward end and said fulcrum and to reach forwardly over the toe end of said sole, and a plurality of outwardly projecting prongs spaced along the forward end of said nose portion, said prongs being disposed only on 15 each side of the longitudinal center line of the tool, all arranged whereby said nose portion will move and pull principally in an upward direction when said tool is rocked on said fulcrum.

3. A lasting tool comprising a handle, opposed 20 lateral arms at one end of said handle, an arcuate nose portion projecting forwardly from said arms and connecting the outer extremities thereof to provide an open space bounded by said arms and said nose portion, and a plurality of 25 outwardly projecting prongs spaced along the forward end of said nose portion.

4. A lasting tool comprising a handle, opposed lateral arms at one end of said handle, an arcuate nose portion projecting forwardly from said 30 arms and connecting the outer extremities thereof to provide an open space bounded by said arms and said nose portion, said nose portion being turned upwardly relative to the plane 35 of said handle and said arms, and a plurality of outwardly projecting prongs spaced along the forward end of said nose portion.

5. A lasting tool comprising pincers having relatively long jaws disposed one above the other and curved downwardly at their ends, a hammer 40 head mounted on the bottom surface of the lowermost jaw closely adjacent the pivot of said pincers, the curved ends of said jaws being spaced from said hammer head to provide a relatively large gap therebetween, and a plurality of 45 outwardly projecting prongs spaced transversely along the end margin of the uppermost jaw.

JOHN T. RIDDELL.
